CLAIM

I claim the ornamental design for a combined display and control unit as shown and described.

DESCRIPTION

FIG. 1 is a top, front, left perspective view of a combined display and control unit in accordance with a first embodiment of my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom view thereof;

FIG. 8 is a top, front, left perspective view of a second embodiment of a combined display and control unit in accordance with my design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and

FIG. 14 is a bottom plan view thereof;

FIG. 15 is a top, front, left perspective view of the combined display and control unit of the first embodiment showing an alternate environment.

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof; and,

FIG. 21 is a bottom plan view thereof.

The broken lines shown represent environmental subject matter and do not form part of the claimed design.

1 Claim, 6 Drawing Sheets
